UNITED STATES PATENT OFFICE.

ELMER O. BEARDSLEY, OF CHICAGO, ILLINOIS, ASSIGNOR TO THE BEARDSLEY & PIPER COMPANY, OF CHICAGO, ILLINOIS, A CORPORATION OF ILLINOIS.

PORTABLE MOLDING MACHINE.

Application filed October 25, 1922. Serial No. 596,722.

To all whom it may concern:

Be it known that I, ELMER O. BEARDSLEY, a citizen of the United States, and a resident of Chicago, in the county of Cook and State 5 of Illinois, have invented certain new and useful Improvements in Portable Molding Machines, of which the following is a full, clear, and exact description.

The invention relates to portable molding 10 machines.

In molding machines of the tractor type, exemplified in Letters Patent No. 1,309,836, dated July 15, 1919, Reissue No. 15,292 dated Feb. 28, 1922 and No. 1,408,796 of March 7, 15 1922, the sand is supplied to the molding machine on the truck from a pile or windrow on the molding room floor, the projector is necessarily idle while the machine is being 20 propelled in the reverse direction to the starting end of the molding room, because the machine cannot deliver sand to the projector while it is travelling backwardly and it is necessary to replace the pile of sand in front of the machine after the return run is 25 made. The necessity of placement of the sand in the path of the machine until after it is returned to the starting point results in a considerable loss of time in the service of the machine.

30 The primary object of the present invention is to overcome this loss of time and to make it possible to turn the machine bodily and horizontally approximately 180°, so that the projector can be operated to fill molds 35 and will be supplied with sand from a pile which has been placed behind the machine whilst it is being operated in one direction. This object is attained by providing means for permitting the bodily rotation of the 40 carriage and its reversal. The sand may be piled in rear of the machine while it is on a run in one direction, to make sand available for the succeeding trip in the reverse direction. This results in a substantial saving of 45 time and makes it possible to run the machine continuously without delays resulting from idle trips and delays incident to placing sand in a pile in front of the machine.

The invention consists in the several novel 50 features hereinafter set forth and more particularly defined by claims at the conclusion hereof.

In the drawings: Fig. 1 is a side elevation 55 of a machine embodying the invention. Fig. 2 is a side elevation of the gearing at the

other side. Fig. 3 is a vertical section of the lower portion of the machine. Fig. 4 is a horizontal section. Fig. 5 is a section on line 5—5 of Fig. 4. Fig. 6 is a rear elevation of the lower portion of the machine, parts being 60 shown in section. Fig. 7 is a section on line 7—7 of Fig. 2. Fig. 8 is a detail of the connection for the lower end of the spring connection for holding raised the foot of the 65 lifting mechanism.

The invention is exemplified in a structure which comprises a truck mounted upon wheels adapted to travel on tracks in the molding room floor; a molding machine of the projector type which is mounted on the 70 truck; conveying and elevating mechanism for delivering sand from a longitudinal pile on the floor in front of the machine to the projector on the truck; and mechanism for propelling the truck so that it will advance 75 into the pile to keep the projector continuously supplied with sand.

The truck-frame comprises sides 10 and 11 which are rigidly connected together by pipes 12 and 13 which are suitably and fix- 80 edly secured to the frame-sides. The rear of the truck is carried by a pair of traction-wheels 21 having toothed peripheries 22 to engage correspondingly toothed rails 24 which are set into the floor of the molding 85 room. The front of the truck is supported by wheels 27 on stud-shafts 28 carried by frame-sides 10 and 11 respectively. The hub of each traction-wheel 21 fits over and bears upon one end of pipe 13. A shaft 26 extends through said pipe and is keyed at its ends to the hubs of said traction-wheels so they will be secured together for conjoint 90 rotation and will propel both sides of the machine equally.

The sand-projector or molding machine illustrated is substantially of the construction exhibited in Patent No. 1,408,493, dated March 7, 1922 and comprises a supporting-standard 35 fixed on the truck, a jib 44 100 pivoted to the standard so as to swing horizontally, an arm 45 pivoted to the outer end of the jib 44, so as to swing horizontally relatively thereto, a sand-projector 46, containing a rotor driven by an electric-motor 105 47 which is mounted to swing with arm 45, a vibratory conveyor-chute 48 containing riddle 48a and mounted to swing with jib 44, a belt 50 mounted to swing with said arm and for feeding sand from chute 48 to 110

the projector, and a case 49 containing mechanism, including a motor, for vibrating the chute 48, all of which may be of the construction set forth in said patent, to which reference may be had for a more detailed description thereof. This mechanism exemplifies a sand-projector which is mounted on the truck and is movable laterally so as to discharge sand into all portions of flasks below the projector at either side of the track. Standard 35 is secured to pipe 13 by clamps 37 and to a bracket 36 which is fixed to pipe 12 by U-bolts 41.

Sand is supplied to the projector from a pile on the floor ahead of the truck by a cross-conveyor comprising a shaft 58 and spiral blades 54 and 55, having lugs 53 adapted to disintegrate the sand in the pile. These screw-conveyors convey the sand inwardly towards the center of the truck. An inclined trough-plate 90 secured to lugs 93 on the frame-sides and medially to lugs 98' on a casing 98, cooperates with the screw conveyors to direct the sand to the center of the truck. An elevator for the sand delivered between the inner ends of screw-conveyors 54, 55 comprises an endless-chain 56 on a sprocket 57 fixed to the conveyor-shaft 58 and a sprocket 59 suitably supported at the upper end of standard 60, and buckets 61 on said chain which scoop the sand from the space between the blades 54, 55 and dump it into a guide 62 which delivers it into conveyor-chute 48 on jib 44. This exemplifies mechanism for conveying sand from a pile in front of the truck and elevating it for delivery to the projector on the truck.

An electric motor 68 is supported by a bracket 19 which is suitably fixed to the truck-frame. This motor drives the cross-conveyor, elevator and the propelling mechanism for the truck. Shaft 58 of the cross-conveyors is driven from said motor by a pinion 71 on the motor shaft, a gear 72 meshing with pinion 71 and mounted on a stud 73 carried by frame-side 11, a pinion 74 which is rigid with gear 72, and a gear 75 meshing with pinion 74 and secured to one end of the shaft 58. The elevator is driven by sprocket 57 which is fixed to shaft 58. The traction wheels are driven to propel the truck to cause it to gradually advance into the sand-pile by an eccentric pin 76 fixed on one end of and rotating with shaft 58, a pawl 78 pivoted to and operated by said pin, a ratchet wheel 79 engaged by said pawl, and a pinion 80 which is rigid with ratchet 79 and rotates on a stud 81 on the frame-side 10. Pinion 80 has teeth conforming to the teeth on the traction-wheels 21 and engages one of them, the other being driven through cross-shaft 26. A dog 82 prevents retraction of ratchet 79.

65 Normally, the truck runs on traction-

wheels 21 and carrying wheels 27. At the end of a run in one direction over the track, the machine will be reversed to face in the opposite direction so that it may feed sand from a pile which has been placed on the track behind the machine while it has been making the run in the first direction. To make it possible to reverse the machine, mechanism is provided for lifting the truck-wheels off the rails so they will clear the floor and be free to swing horizontally through approximately 180° to face the machine in the opposite direction. This lifting mechanism comprises a foot or base 95 which is fixed to the lower end of a stem or piston 96 which is slidably mounted in the cylinder 97 of a casing 98. This casing is secured to the truck frame by a rod 99 which extends through bracket 36 and by bolts 94 to standard 35. Cylinder 97 and the entire truck are rotatable around the stem 96. The latter is provided with packing 100, so that when fluid under pressure is forced into the cylinder 97, the stem 96 and foot 95 will be forced downwardly until the foot 95 bears upon the floor. Thereafter, the fluid under pressure will lift the cylinder with its casing 98 and the truck with all of the mechanisms mounted thereon, away from the floor until the traction and carrying wheels will clear the rails 24 and be free to swing laterally.

Foot 95 and the truck-lifting mechanism are located at the center of gravity of the entire machine, so that when it is lifted at that point, all portions of the machine will be elevated sufficiently to clear the floor and permit the entire machine to be turned horizontally. During rotation of the machine, the projector arm 44 will be swung inwardly close to standard 35.

Fluid, such as water or oil for operating the lifting mechanism, is contained in a box 101 which is secured at 102 to frame-pipe 13. A hand-pump to force the fluid from the chamber 103 in box 101 into the cylinder 97 comprises a cylinder 104, a piston 105 working in said cylinder, a hand-lever 106 pivoted at 107 to the upper end of the piston 104 and fulcrumed at 108 on a link 109 which has its lower end pivoted at 110 to the top of the box 101. Fluid from chamber 103 enters the pump-cylinder on its suction-stroke through a check-valve 111, and piston 105 forces the fluid through a duct 112 and pipe 113, into the upper end of the cylinder 97 of the lifting mechanism. A check-valve 114 is included in pipe 113 to prevent back-flow of the fluid into the pump. A return-pipe 115 is connected to pipe 113, controlled by a valve 116 and connected to discharge fluid from the cylinder when said valve is open, into chamber 103 in box 101. In operation, the pump-lever 106 will be operated until sufficient fluid has been forced into

cylinder 97 to operate piston 96 downwardly to cause foot 95 to bear upon the floor and to elevate the cylinder, truck and mechanisms carried thereby, sufficiently to permit horizontal turning of the machine. Fluid under pressure while held in the cylinder 97 will retain the truck elevated and the entire machine may then be turned around the stem 96 carried by the foot 95. This permits the machine to be swung through an arc of 180° so that it may face and be operable in opposite directions on the track. When reversal has been made, the operator will open valve 116 so the fluid in cylinder 97 will flow back through pipe 115 into the chamber 103 in box 101. Valve 116 is kept closed while the pump is being operated to fill the cylinder 97. A spring 117 has its upper end connected to bracket 36 and its lower end to an arm 118 which is pivotally held on stem 96 and lifts the foot 95 clear of the floor when the machine has been lowered so its carrying wheels rest on the track. A collar 119, which is fixed to the stem 96 above arm 118, vertically confines the arm 118 on said stem. A link 120 is pivoted to arm 118 at one end 121 and loosely pivoted to a stud 122 on the trough-plate 90 to turn said arm horizontally with the truck. The loose connection between stud 122 and link 120 permits the arm to rise and fall with foot 95 as the truck is raised or lowered.

The invention exemplifies a molding machine of the tractor type, in which provision is made for lifting it so it may be turned to operate in either direction along a track. This is an important feature in machines of this class, because it makes it possible to build up a pile of sand behind the machine while it is being operated in one direction, so as to have sand available for delivery to the projector during a run in the opposite direction.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of a truck adapted to travel over a floor, a molding machine on the truck, means to feed sand from a pile at the front of the truck when it is facing in one direction and mechanism for lifting the truck to clear the floor and permit it to be turned horizontally over the floor to render the feed means operable with a pile when the truck is facing in the other direction.

2. In a machine of the character described, the combination of a truck adapted to be moved over a floor, a molding ma-

chine on the truck, mechanism on the truck for conveying sand to said machine, and mechanism for lifting the truck to permit it to be turned horizontally over the floor.

3. In a machine of the character described, the combination of a truck, a molding machine on the truck, a cross-conveyor for sand on the truck, an elevator on the truck for lifting sand for delivery to said machine, and mechanism for lifting the truck to permit the truck and cross-conveyor to be turned horizontally.

4. In a machine of the character described, the combination of a truck adapted to be moved over a floor, means to deliver sand from a pile on the floor while the truck is facing in one direction, means for lifting the truck off the floor and pivotally sustaining it so it can be turned horizontally to face in opposite directions.

5. In a machine of the character described, the combination of a truck, a molding machine on the truck, mechanism on the truck for conveying sand to said machine, and means for lifting the truck off the floor and pivotally sustaining it so it can be reversed to face in opposite directions.

6. In a machine of the character described, the combination of a truck, a molding machine on the truck, a cross-conveyor for sand on the front of the truck, an elevator on the truck for lifting sand for delivery to said machine, and means for lifting the truck off the floor and pivotally sustaining it so it can be reversed to face in opposite directions.

7. In a machine of the character described, the combination of a track, a truck adapted to run on said track in either direction, a molding machine on the truck, means to feed sand to the machine while the truck is facing in one direction and mechanism for lifting the truck to clear the track and permit it to be turned horizontally to render the feed means operable to receive sand while the machine is facing in the opposite direction.

8. In a machine of the character described, the combination of a track, a truck adapted to run on said track in either direction, mechanism on the truck for propelling it over the track, means to feed sand to the machine while the truck is facing in one direction, a molding machine on the truck, and mechanism for lifting the truck to clear the track and permit the truck to be rotated horizontally to render the feed means operable to receive sand while the machine is facing in the opposite direction.

9. In a machine of the character described, the combination of a track, a truck adapted to run on said track in either direction, mechanism on the truck for propelling it over the track, a molding machine on the truck, mechanism at the front of the

truck for conveying sand to said machine from a pile on the floor, and mechanism for lifting the truck to clear the track and permit it to be turned horizontally to face in either direction.

10. In a machine of the character described, the combination of a truck, a molding machine on the truck, mechanism for conveying sand to said machine, and mechanism operable by fluid under pressure for lifting the truck and permitting it to be turned horizontally.

11. In a machine of the character described, the combination of a wheeled truck, a molding machine on the truck, mechanism on the truck for conveying sand to said machine, and mechanism operable by fluid under pressure for lifting the truck to permit it to be turned horizontally.

12. In a machine of the character described, the combination of a truck adapted to travel over a floor, a molding machine on the truck, a foot, a piston and cylinder to one of which the foot is connected, and means for forcing fluid under pressure into the cylinder to lift the truck relatively to the foot, so the truck may be turned.

13. In a machine of the character described, the combination of a truck adapted to travel over a floor, a molding machine on the truck, mechanism on the truck for conveying sand to said machine, a foot, a piston and cylinder to one of which the foot is connected, and means on the truck for forcing fluid under pressure into the cylinder to lift the truck relatively to the foot.

14. In a machine of the character described, the combination of a truck adapted to travel over a floor, a molding machine on the truck, mechanism on the truck for conveying sand to said machine, a foot, a piston and cylinder to one of which the foot is connected, a pump on the truck for forcing fluid under pressure into the cylinder to lift the truck relatively to the foot, and mechanism for controlling the fluid back and forth between the cylinder and the pump.

15. In a machine of the character described, the combination of a truck, a molding machine on the truck, mechanism on the

truck for conveying sand to said machine, lifting mechanism for the truck, comprising a foot, and means for holding the foot raised above the floor.

16. In a machine of the character described, the combination of a truck adapted to travel over a floor, a molding machine on the truck, mechanism on the truck for conveying sand to said machine, lifting mechanism for the truck comprising a piston and a cylinder, a pump for supplying fluid under pressure to and from the cylinder, a foot connected to one of the elements of the lifting mechanism, and means for holding the foot in raised position above the floor. 55

17. In a machine of the character described, the combination of a truck adapted to travel over the floor, a molding machine on the truck, mechanism on the truck for conveying sand to said machine, lifting mechanism for the truck comprising a foot, and a spring for holding the foot raised above the floor. 70

18. In a machine of the character described, the combination of a truck adapted to travel over a floor, a molding machine on the truck, mechanism on the truck for conveying sand to said machine, lifting mechanism comprising a cylinder and a piston in the cylinder, a foot, the cylinder and piston being relatively rotatable to permit the truck to turn horizontally, a pivoted arm pivotally connected to the piston, and means to cause the arm to rotate with the truck. 75

19. In a machine of the character described, the combination of a truck adapted to travel over a floor, a molding machine on the truck, mechanism on the truck for conveying sand to said machine, lifting mechanism comprising a cylinder fixed to the truck, a piston in the cylinder, a foot secured to the piston, the cylinder and piston being relatively rotatable to permit the truck to turn horizontally, an arm pivotally connected to the piston, a spring for lifting the foot 90 connected to said arm, and means to cause the arm to rotate with the truck. 95

Signed at Chicago, Illinois, this 25th day of September, 1922.

ELMER O. BEARDSLEY.
